UNITED STATES PATENT OFFICE.

EDWIN W. STONE, OF LONGMEADOW, MASSACHUSETTS, ASSIGNOR TO BIGELOW-HART-FORD CARPET COMPANY, OF THOMPSONVILLE, CONNECTICUT, A CORPORATION OF MASSACHUSETTS.

LOOM.

Application filed April 27, 1928. Serial No. 273,175.

This invention relates to looms and is more particularly directed to a structure wherein the lay may be supported and operated at intervals transversely of the loom without at any time interfering with the shed forming mechanism.

In recent years there has been a constantly increasing demand for wider and wider fabric, such, for instance, as carpets and rugs, and this has led to an increase in the loom width and consequently in the length of the lay from end to end transversely of the loom. With this increased length of the lay a difficulty has arisen in that the lay itself was rendered liable to bend or spring backward in the center relative to the ends which were connected to the lay operating means or lay swords, with the result that the fabric produced would have the weft threads curved transversely and consequently cause bulging of the finished fabric when laid upon the floor.

In some cases, also, it may be desirable at times in changing the character of the fabric being produced, as, for instance, changing from a light to a heavier fabric, with the same length of lay, to prevent the occurrence of the backward spring or buckling of the lay, by introducing between the side swords, lay supporting and operating devices, without at the same time interfering with the shed forming mechanism.

Since the width of the fabrics woven by the loom may vary, it has also been desirable that the width of the loom and consequently the length of the breast beam and lay from side to side of the loom be correspondingly varied to suit the character and width of fabric produced.

One of the objects of the present invention is to provide a loom structure wherein additional lay supporting and operating means may be utilized between the side swords of the lay without at the same time interfering with the shed forming mechanism, and operating all of the lay supporting and operating means from a lay operating shaft which is itself disposed frontward of the shed forming mechanism and in non-interfering relation therewith.

In accordance with one aspect of the invention, the loom is provided with a front frame extending transversely of the loom and having its back wall frontward of the

shedding mechanism, and associated with the front frame there is provided a lay operating shaft and connections between the operating shaft and the lay, all disposed frontward of the shedding mechanism, with the result that at intervals throughout the width of the loom or length of the lay, provisions may be made for supporting and operating the lay intermediate the side swords.

In accordance with another aspect of the present invention, a selfcontained unit is provided, including as part thereof a portion of the front frame, an auxiliary lay sword and operating connections between the lay sword and the lay operating shaft, with the result that since these parts are all disposed frontward of the shedding mechanism and in noninterfering relation therewith, the lay may be supported and operated at intervals throughout its length. Another advantageous feature resulting from the selfcontained unit is that the loom itself may be varied in width as dictated by the width of the fabric desired by the introduction of one or more of such selfcontained units disposed at intervals between the ends of the lay.

The invention and various novel features thereof and new combination of parts will best be made clear from the following description and the accompanying drawings of one good form thereof.

In the drawings:

Fig. 1 is a front perspective view of a loom containing the present invention and having some of the parts broken away for illustrative purposes;

Fig. 2 is a fore-and-aft section through a loom, such as that illustrated in Fig. 1, and containing the present invention;

Fig. 3 is a fore-and-aft section through one of the selfcontained lay supporting and operating units;

Fig. 4 is a perspective view on an enlarged scale of one of the lay supporting and operating units showing some of the parts broken away;

Fig. 5 is an enlarged detail in perspective showing a portion of the toggle operating means comprised in each unit;

Fig. 6 is a plan view with parts broken away showing a number of the lay supporting and operating units assembled together

for determining the width of the loom and consequently of the fabric that is to be produced; and

Fig. 7 is an enlarged detail showing part 5 of the lay operating shaft and the toggle connection therefrom to the lay.

The side frames of the loom back of the front frame and lay supporting and operating units may be of any desired character 10 and, as indicated in Fig. 2, the side frames 1, only one of which is indicated, support the usual warp beams 2, 3 and 4 or any number, from which the warp threads *a* are delivered to the weaving instrumentalities.

It may be desirable in connection with the present invention to operate the loom from a motor rather than from belting to a line shaft, although, so far as the present invention is concerned, this detail is not of controlling importance. However, in the present instance of the invention there is mounted at one side of the loom a motor 5, which is indicated in a general way in Fig. 2, and connected to the motor shaft 6 is a pinion 7 which meshes with a gear 8 mounted on a shaft 9 at the side of the loom. The shaft 9 carries the pinion 10 from which the lay actuating shaft may be conveniently operated, as will further appear.

The shedding mechanism may be of any usual type and in the present instance of the invention it is indicated by the harness frames 11 and the cords 12, the latter of which may carry lingoies 13. The character 35 of the shedding mechanism and its operative means may be varied in accordance with the character of the fabric to be produced and may comprise either pattern control harness mechanism or jacquard devices.

The present invention is primarily concerned with the parts of the loom forward of the shedding mechanism, and in accordance therewith these parts are so positioned with respect to the shedding mechanism that the lay operating means, as will be further explained, is wholly forward of the shedding mechanism and in non-interferring relation therewith.

Mounted upon the ties or cross-members 50 14 forward of the loom sides are the standards 15 which may be bolted to the cross-members 14 or secured thereto in appropriate manner for rigidity of structure.

Mounted on the standards 15, of which 55 there may be any suitable number, is the front frame 16, the back wall 17 whereof extends transversely of the loom forward of the shedding mechanism. The front frame 16 is of novel construction in that the front portion thereof constitutes in effect the breast beam of the loom, and the frame is preferably formed as a box-like structure, having strengthening walls 18 which extend between the front and back walls of the 65 front frame, as more clearly indicated in

Fig. 3, and constitute rigid reinforcing members for the back wall, which, as will hereinafter appear, takes the thrust of the lay operating devices.

The top portion 19 of the front frame has 70 mounted thereon the cloth plate 20, the rear edge portion 21 of which is close to the fell of the cloth being woven, the construction being such that as the cloth *b* is woven, in the usual manner, it is drawn forward 75 over the guide or spike roll 22 from which it is guided to the cloth take-up mechanism, which may be of any usual character. In order to economize the space occupied by the take-up mechanism and guide or spike 80 roll 22, the front frame 16 is inwardly curved, as at 23, as shown in the present instance of the invention.

Mounted at each side of the loom and operatively connected to the end portions of 85 the lay are the lay swords 24, one of which is shown in Fig. 1, and mounted upon the lay swords 24 and extending between them is the lay 25. Each of the lay swords 24, one at each side of the loom, is mounted for 90 rocking movement upon a rock shaft 26 which extends transversely of the loom forward of the shedding mechanism, and inasmuch as the cap or hand rail 27 of the lay structure should be appropriately supported 95 at each side of the loom, each of the lay swords 24 is carried upwardly, as at 28, and connected at the ends thereof to the hand rail or reed cap, as indicated in Figs. 1 and 2.

To accommodate the upwardly extending 100 portions 28 of the end lay swords, the end portions of the front frame at the rear thereof and at each side are carried backwardly, as indicated at 29, Fig. 6, the effect being that the end lay swords having their upward 105 extensions 28 may operate properly without interfering with the contiguous portions of the front frame.

As hereinbefore indicated, the present invention contemplates that the lay may be 110 supported and operated at different points of its length between the side lay swords, without interference with the shedding mechanism and the operating parts of the loom, and to this end the present invention 115 provides one or more selfcontained lay supporting and operating units which may be interposed between the side lay swords and operated from the lay operating shaft, as will now be explained.

The lay rock shaft 26 for the support of 120 the side lay swords extends transversely of the loom throughout the width thereof and where one or more of the selfcontained lay supporting and operating units is interposed 125 between the side lay swords, the rock shaft 26 also extends through bearings 30 carried by the standards 15 adjacent each lay operating unit.

Likewise extending transversely of the 130

loom throughout its width is the lay operating shaft 31, and bearings 32 are provided on the standards 15 as a support for the lay operating shaft. Both the rock shaft 26 and the lay operating shaft 31 are thus mounted in bearings carried by the standards of the lay supporting and operating units and are disposed frontwardly of the shedding mechanism, as indicated in Fig. 2, with the result that neither shaft interferes with the proper manipulation of the shedding mechanism. The lay operating shaft 31 is preferably disposed below the front frame 16 and is provided with a series of crank arms 33 which serve as actuating means for the side lay swords and the auxiliary lay swords disposed therebetween.

Each of the units comprises an auxiliary lay sword 34, Figs. 1 and 2, mounted on the lay rock shaft 26, and each of the auxiliary lay swords 34 is connected to the lay 25 preferably at its under side, as indicated in Fig. 2.

Each of the lay swords 24 and 34 has a frontwardly extending projection 35 to which is pivotally connected at 36 a link 37 forming a member of a toggle operating device. Pivotally connected to the link 37 at 38 is the link 39 constituting a second member of the toggle operating means, and such link 39 is mounted on a fixed center 40 connected to the back wall 17 of the front frame. Connected to the two toggle members 37 and 39 is a link 41 associated with a crank 33 on the lay operating shaft 31, the construction being such that upon rotative movement being imparted to the lay operating shaft 31, the toggle members will be given an operating movement to carry the lay forward and backward while the thrust of the toggle members is sustained by the fixed center 40 carried by the back wall 17 of the front frame 16. It will be noted from this construction that the entire lay operating means, both of the side lay swords and the auxiliary lay swords, are disposed frontward of the shedding mechanism and in noninterfering relation therewith, and consequently any number of lay supporting and operating units may be disposed throughout the length of the lay, either to support the latter from backward springing movement during the beat-up or to increase the width of the loom.

The character of the toggle connection between the side lay swords or the auxiliary lay swords and operating shaft may be varied, but in order to insure against any side stress or twisting movement in the toggles, they are preferably formed as indicated in Fig. 5, wherein is shown the two toggle members 39 having the fixed center 40 connected to a part of the front frame, and each provided with a bifurcated end portion 42 adapted to be connected to a similarly bifur-

cated end portion formed on the toggle members 37, as indicated in Fig. 4. The toggle members 37 may be duplicated, one each side of the movable center 38, with the result that the stress of the toggle members 70 will be evenly distributed without twisting or bending movements during their operative functioning.

Since the back wall 17 of the front frame preferably is to bear the thrust of several 75 toggle mechanisms employed for actuation of the lay, the front frame 16 by its strengthening members 18 imparts rigidity to the back wall 17 of the front frame and the operating connections of the toggles with 80 the lay are carried upwardly in close proximity to the beat-up portion of the lay.

From the construction described it will be apparent that the present invention provides lay supporting and operating units of 85 self-contained character which may be disposed at different points transversely of the lay to thereby prevent any backward springing movement or bending of the lay during the beat-up, with the consequent production 90 of perfect cloth. It will also be observed that the entire system constituting each unit for lay support and operation is disposed frontwardly of the shedding mechanism and consequently permits variation in the shedding mechanism without interference therewith, and that the loom itself may be varied in width and the lay prevented from springing backward by the employment of one or more of the lay supporting and operating 95 units. As indicated in Fig. 1, the front frame 16 is composed of independent sections secured in end-to-end relation and supported by the standards 15 to form a rigid structure. These sections may be economically formed by metal castings, and where the loom is to be varied in width one or more of the front frame sections may be introduced or removed, and preferably each of said sections is associated with an auxiliary 100 lay sword and operative connection with the lay operating shaft, with the result that regardless of the width of the loom, the lay will be actuated from the lay operating shaft at intervals throughout its length and 105 thus any tendency to spring between the ends during weaving will be effectively avoided even though the loom may be of unusual width.

Since the lay receives the full force of the 110 beat-up it is usually desirable that the lay batten be of one continuous piece of sufficient rigidity to stand the strains, and in some cases the front frame may likewise be cast in a single piece of desired length so that in changing the width of the loom 115 under these circumstances it is preferable to provide a separate lay and front piece for each change, but in any event, the lay supporting and operating units constituted 120

by the auxiliary lay swords and their operating connections with the lay operating shaft will be employed at intervals throughout the width of the loom to overcome any 5 tendency for the lay to spring between its ends during weaving. This desirable result is most effectively secured by forming the operating connections between the lay and lay operating shaft as toggles which act 10 positively in both directions frontward of the shedding mechanism and transmit their combined thrust during beat-up to the front frame casting.

Since the lay actuating shaft 31 extends 15 transversely of the loom below the back wall 17 of the front frame and in a vertical plane frontward of the back wall, the lower wall of the front frame 16 is slotted to permit the operating devices attached to the 20 lay actuating shaft to pass therethrough, and should it be desired to give the lay two beat-up movements on each operation of the lay operating means, it is only necessary to give proper throw to the cranks on the crank 25 shaft to first beat-up as the toggles pass their upward center and again beat-up as the toggles are brought downwardly past such center.

What is claimed is:

30 1. In a loom, the combination of the lay and shedding mechanism, a lay operating shaft extending transversely of the loom frontward of the shedding mechanism, a front frame extending transversely of the loom with its back wall frontward of the 35 shedding mechanism, means at each side of the loom connected to the lay operating shaft for operating the lay, a plurality of toggles disposed at intervals between said means having fixed centers supported by the back wall of the front frame, and link connections wholly in front of the shedding mechanism between each toggle and the lay operating shaft.

45 2. In a loom, the combination of the lay and shedding mechanism, a lay operating shaft extending transversely of the loom in front of the shedding mechanism, a front frame extending transversely of the loom 50 with its back wall frontward of the shedding mechanism and back of a vertical plane passing through the longitudinal axis of the lay operating shaft, lay swords at each side of the loom and auxiliary lay swords there- 55 between, toggles operatively connected to each of the lay swords and having fixed centers supported by the back wall of the front frame, and link connections between each of the toggles and the lay operating shaft for 60 supporting and operating the lay at intervals transversely thereof.

65 3. In a loom, the combination of the lay and shedding mechanism, a lay operating shaft extending transversely of the loom frontward of the shedding mechanism, a

front frame formed of separate sections secured together extending transversely of the loom with its back wall frontward of the shedding mechanism, means at each side of the loom connected to the lay operating 70 shaft for operating the lay, a plurality of toggles disposed at intervals between said means having fixed centers supported by the back wall of the front frame, and link connections wholly in front of the shedding 75 mechanism between each toggle and the lay operating shaft.

4. In a loom, the combination of the lay and shedding mechanism, a lay operating shaft extending transversely of the loom 80 frontward of the shedding mechanism, a front frame having back, front, and bottom walls all frontward of the shedding mechanism, lay swords at each side of the loom and auxiliary lay swords therebetween passing through the bottom wall of the front frame, toggles operatively connected to the lay swords and having fixed centers supported by the back of the front frame frontward of the shedding mechanism, and link 85 connections with each of the toggles and lay operating shaft for supporting and operating the lay at intervals transversely thereof.

5. In a loom, the combination of the lay and shedding mechanism, a lay operating shaft extending transversely of the loom frontward of the shedding mechanism, a lay sword at each side of the loom and auxiliary lay swords at intervals, toggles operatively connected to the lay swords and lay operating shaft, a box-like front frame above the lay operating shaft having its back wall frontward of the shedding mechanism and braced by the side portions of the box-like frame, and fixed center of the 105 toggles supported by the back wall of the front frame above the lay operating shaft.

6. In a loom, the combination of the lay and shedding mechanism, a lay operating 110 shaft extending transversely of the loom frontward of the shedding mechanism, lay swords at each side of the loom and auxiliary lay swords at intervals between them, toggles operatively connected to the lay 115 swords and lay operating shaft, and a front frame extending transversely of the loom above the lay operating shaft frontward of the shedding mechanism, and a fixed center connection between each toggle and the back 120 wall of the front frame frontward of the shedding mechanism.

7. In a loom, the combination of the lay and shedding mechanism, a lay operating shaft extending transversely of the loom 125 frontward of the shedding mechanism, lay swords at each side of the loom and auxiliary lay swords at intervals between them, toggles operatively connected to the lay 130 swords and lay operating shaft, and a front

frame extending transversely of the loom above the lay operating shaft forward of the shedding mechanism and constituting a housing for the toggles, and a fixed center connection between each toggle and the back wall of the front frame forward of the shedding mechanism.

8. In a loom, the combination of the lay and shedding mechanism, a lay operating shaft extending transversely of the loom forward of the shedding mechanism, lay swords at each side of the loom, an auxiliary lay sword disposed between the side lay swords, a front frame having its back member forward of the shedding mechanism, lay operating devices connected to each of the lay swords and lay operating shaft and having fixed bearings on the back member of the front frame, and bracing elements extending frontwardly from the back member of the front frame to brace the back member against the forward thrust of the lay operating devices.

9. In a loom, the combination of the lay and shedding mechanism, lay swords at each side of the loom, a lay operating shaft extending transversely of the loom forward of the shedding mechanism and operatively connected to the side swords, a selfcontained lay supporting and operating unit adapted to be inserted between the side lay swords to increase the loom width, and comprising a support, a front frame mounted on the support and having its back member forward of the shedding mechanism when in place, an auxiliary lay sword, and lay operating devices having a fixed center on the back member of the unit.

10. In a loom, the combination of the lay and shedding mechanism, lay swords at each side of the loom, a lay operating shaft forward of the shedding mechanism, a divided front frame extending transversely of the loom, and a selfcontained lay supporting and operating unit adapted to be inserted between the divisions of the front frame for varying the width of the loom, and comprising an auxiliary lay sword, a front frame complementary of the divided front frame, and lay operating mechanism for connection with the lay operating shaft.

11. In a loom, the combination of the lay and shedding mechanism, lay swords at each side of the loom, a divided front frame extending transversely of the loom, a lay operating shaft forward of the shedding mechanism, and a selfcontained lay supporting and operating unit between the parts of the divided front frame and comprising a section of front frame complementary to the divided front frame for varying the width of the loom, supports therefor, an auxiliary lay sword, and means for operatively connecting the auxiliary lay sword to the lay operating shaft.

12. In a loom, the combination of the lay and shedding mechanism, lay swords at each side of the loom, a divided front frame permitting the width of the loom to be varied, a lay operating shaft, and a selfcontained lay supporting and operating unit having a section of front frame complementary of the divided front frame, an auxiliary lay sword, and operating means for connecting the auxiliary lay sword to the lay operating shaft.

13. In a loom, the combination of the lay and shedding mechanism, lay swords at each side of the loom, a divided front frame permitting the width of the loom to be varied, a cloth plate supported on the divided front frame, a lay supporting and operating unit section adapted for insertion between the ends of the separated parts of the front frame when the width of the loom is increased and comprising supporting standards, a section of the front frame complementary of the divided front frame supported by said standards, means for securing the standards to the loom frame, an auxiliary lay sword, an operating shaft, and toggle means for operatively connecting the auxiliary lay sword to the operating shaft when the unit section is added to the loom to increase the width thereof.

14. In a loom for weaving fabrics, the combination of the lay and shedding mechanism, a lay rock-shaft, a front frame extending transversely of the loom and having a backwardly extending member terminating forward of the shedding mechanism, a lay operating shaft extending transversely of the loom forward of the shedding mechanism, and operating connections between the lay and lay operating shaft at intervals throughout the length of the lay and forward of the shedding mechanism including a member connected to the front frame to transmit the strain of beat-up to the front frame that the lay may not be sprung during weaving.

15. In a loom for weaving fabrics, the combination of the lay and shedding mechanism, a lay operating shaft extending transversely of the loom forward of the shedding mechanism, a front frame composed of independent and detachable sections secured in end-to-end relation for varying the width of the loom, and lay operating means connected to the lay operating shaft at intervals throughout the length of the lay forward of the shedding mechanism.

16. In a loom for weaving fabrics, the combination of the lay and shedding mechanism, a lay operating shaft extending transversely of the loom forward of the shedding mechanism, a front frame composed of independent and detachable sections secured in end-to-end relation for varying the width of the loom, standards for supporting the different front frame sections, and lay op-

erating means connected to the lay operating shaft at intervals throughout the length of the lay frontward of the shedding mechanism.

17. In a loom for weaving fabrics, the combination of the lay and shedding mechanism, the lay operating shaft mounted in front of the shedding mechanism and extending transversely of the loom, lay operating mechanism connected to the lay and lay operating shaft at the ends of the lay and at intervals between the ends of the lay all frontward of the shedding mechanism and acting upon the lay at intervals throughout its length to impart lay beat-up movements that the lay may not be sprung backward between its ends during weaving.

18. In a loom for weaving fabrics, the combination of the lay and shedding mechanism, the lay rock shaft, the lay operating shaft extending transversely of the loom above the lay rock-shaft frontward of the shedding mechanism, toggle connections between the

lay operating shaft and lay at intervals throughout the length of the lay and frontward of the shedding mechanism to impart beat-up impulse to the lay at intervals throughout its length that it may not become curved during weaving.

19. In a loom for weaving fabrics, the combination of the lay and shedding mechanism, a lay rock-shaft, a front top frame having a member extending back of the lay and terminating frontward of the shedding mechanism, a lay operating shaft extending transversely of the loom frontward of the shedding mechanism above the lay rock-shaft and provided with crank arms at intervals of its length, and a series of toggles connecting the crank arms and lay and having their thrust members connected to the front frame member.

In testimony whereof, I have signed my name to this specification.

EDWIN W. STONE.
